UNITED STATES PATENT OFFICE.

MAX HERSKOVITZ, OF CHICAGO, ILLINOIS.

SHADE-HOLDER.

1,303,898.

Specification of Letters Patent. Patented May 20, 1919.

Application filed April 29, 1916. Serial No. 94,409.

To all whom it may concern:

Be it known that I, MAX HERSKOVITZ, a citizen of the United States, and a resident of Chicago, in the county of Cook and State of Illinois, have invented certain new and useful Improvements in Shade-Holders, of which the following is a specification.

The object of my invention is to provide in a unitary structure means providing a seat for an upper shade and suspending means for a lower inverted shade depending therefrom.

A further object of my invention is to provide in combination with the said unitary structure a shade holder coöperating therewith to clamp the upper shade on its seat.

A further object of my invention is to provide such a unitary structure and a shade holder of such construction that they may be detachably secured together, whereby the unitary structure is suspended solely from the said shade holder; and with these and other objects in view my invention consists of the parts and combination of parts as will be hereinafter set forth.

In the drawings:

Figure 1 is a central vertical sectional view illustrating my invention.
30 Fig. 2 is a side elevation of the shade holder detached.

Figs. 3, 4, and 5, are detail sectional views, parts being in elevation showing further embodiments of my invention.

35 The reference numeral 1 designates a shade holder the dome of which is provided with an aperture 2 for the passage of conductor cord 3. The wall of the holder is provided with screw threads 4 and below 40 these threads the wall is flared outwardly at 5 whereby an increased diameter is provided, whereby the holder may fit over the upper flange bead or collar 6 of an upper shade 7, the object of which is to hold the 45 upper shade on its seat as will be hereinafter pointed out.

The lower shade holder is a unitary structure and comprises, in the preferred form, a sleeve 8, open at both ends and provided 50 at its upper end with screw threads 9 which are adapted to intermesh with the threads 4 of the shade holder 1, whereby the unitary shade holder is detachably suspended from the shade holder 1. The sleeve 8 is 55 provided at its lower end with a seat 10, of suitable conformation, for the upper shade

7, the flared end 5 of the dome 1 clamping or holding the upper shade in proper position on said seat.

Depending from the seat 10 are means for suspending a lower inverted shade 11 from said seat and beneath the upper shade 7, and for the purpose of illustrating my invention I have elected to show said suspending means as consisting of three outwardly spreading and downwardly extending arms 12, each of which is provided at their lower ends with any suitable clamping member 13, adapted to receive and hold the edge of the inverted lower shade 11 whereby the shade is held in suspension. These clamps may be provided with pins or other devices 13^a, but it will be understood that my invention is not limited to the particular form of clamp shown because the form of 75 clamp will depend entirely on the configuration of the upper edge of the inverted shade 11 and also depend on whether or not arms or chains are used as the suspending medium. The primary object of my invention being the unitary structure.

In order to adapt my invention to all kinds of repair work so that the unitary structure may be used in connection with shade holders on old fixtures, I may flare 85 the upper end of the sleeve as shown at 14 in Fig. 5 for coöperative engagement with the usual clamping screws 15 found in ordinary shade holders. Otherwise the unitary structure is the same as heretofore described. 90

Or I may, instead of flaring the upper end of the sleeve, provide elongated openings 16 through the sleeve for the reception of the ends of the usual clamping screws 15; and where the shade holder is not large 95 enough at the bottom to receive the collar, bead or rib at the top of the upper shade, I provide a supplemental member 17 adapted to surround said collar, bead or rib, and said member is held in place by reason of 100 the fact that it is clamped between the shade holder and the upper shade, as will be readily understood by those skilled in the art.

I may, if found desirable, or necessary for 105 certain kind of work, make the dome 18 of the shade holder detachable as shown in Fig. 3 and have a coöperative screw thread interlock 19 between the holder and dome.

Many changes may be made in the details 110 of construction within the scope of the claims, without departing from the inven-

tive thought herein disclosed, hence I would have it understood that my invention is not limited to the details of construction shown in the illustrated embodiment.

5 What I claim is:

1. A shade holder for a light inclosing bowl, and a reflector superposed over said bowl, said device consisting of a socket cover having a cylindrical threaded body terminating at its lower end in a flaring skirt, a sleeve removably mounted within said body and projecting downward therefrom, said sleeve having an annular flange at its lower end located below the edge of said skirt, said sleeve being adapted to be embracingly engaged by the neck of the shade or reflector, and said flange constituting a seat upon which said shade or reflector is supported, and arms carried by said sleeve and adapted for engagement with the upper edge of the light inclosing bowl.
2. A shade holder for a light inclosing

bowl, and a reflector superposed over said bowl, said device consisting of a socket cover having a cylindrical threaded body 25 terminating at its lower end in a flaring skirt, a sleeve removably mounted within said body and projecting downward therefrom, said sleeve having an annular flange 30 at its lower end located below the edge of said skirt, said sleeve being adapted to be embracingly engaged by the neck of the shade or reflector, and said flange constituting a seat upon which said shade or reflector is supported, arms secured to said sleeve 35 and hooks formed upon the ends of said arms for supportingly engaging the rim of a bowl.

In testimony whereof I affix my signature in the presence of two witnesses.

MAX HERSKOVITZ.

Witnesses:

G. FRANKLIN,
JOHN EGOLF.
